UNITED STATES PATENT OFFICE

JOSEPH E. LARSON, OF CLARKS, NEBRASKA

STOCK SEPARATOR

Application filed July 9, 1928. Serial No. 291,394.

The invention relates to improvements in barriers for permitting small pigs or other stock to pass, for instance to a feed trough, while preventing larger stock from having access to the destination of the small stock. The present disclosure of the invention is in connection with a hog feeder and while this is its principal application, it is to be understood that it is not restricted to this particular field of use.

It is the object of the invention to provide an exceptionally simple and inexpensive, yet an efficient and reliable construction which will permit small stock to readily pass, will not permit large stock to pass, and will readily allow the large stock to withdraw from the barrier should they wedge their heads into the spaces through which the small stock passes.

With the foregoing in view, the invention resides in the novel subject matter hereinafter described and claimed, description being accomplished by reference to the accompanying drawings.

Fig. 1 is a side elevation of a hog feeder embodying the invention.

Fig. 2 is a horizontal sectional view on line 2—2 of Fig. 1.

Fig. 3 is a transverse sectional view on line 3—3 of Fig. 1.

Fig. 4 is a horizontal sectional view on the correspondingly numbered line of Fig. 3.

In the drawings above briefly described, 5 denotes a feeding house whose general construction may be as desired. Within this house, I have shown a feed trough 6 and a hopper 7 for supplying feed thereto, a door 8 being provided in the roof of the house, through which to fill the hopper. Each of 40 the side walls 9 of the house 5, constitutes one of the improved barriers and as they are both of the same construction, only one will be described.

The wall 9 is formed with a suitable number of rectangular door openings 10 and with flat vertically disposed wall portions 11 at opposite sides of said openings. A door 12 is provided for each opening 10 and is of considerably less width than said opening.

These doors are hinged at 13 to the wall por-

tions 11 at one side of the openings 10 with their free edges 14 spaced from the other sides of said openings. Flat barriers 15 lie against the wall portions 11 at said other sides of the openings 10 and are adjustable toward and from the free edges 14 of the doors 12, to vary the width of the spaces 16 between said barriers and door edges, to allow only stock under predetermined size to pass. The upper and lower ends of the barriers 15 are formed with horizontal slots 17 registering with bolt holes 18 (Fig. 4) in the wall portions 11, and clamping bolts 19 are passed through these slots and openings for tightly clamping the barriers 15 against the wall portions 11 to secure the former in adjusted position.

Due to the provision of an appropriate stop such as a sill strip 20, the doors 12 cannot be swung inwardly, and these doors are yieldably held in their closed positions, by coiled springs 21 connected thereto, the inner ends of these springs being anchored to the hopper 7, in the present disclosure.

The construction described, allows the small pigs to pass but prevents the larger ones from doing so. However, in case the large stock should wedge their heads through the openings 16 and then find they can get no further, they may readily withdraw, as the springs 21 permit outward swinging of the doors 12 for this purpose. These swinging doors also come into play in case the small stock crowd each other when leaving the house 5, more than one attempting to pass through an opening 16 at the same time.

It will be seen from the foregoing that while the invention is exceptionally simple and inexpensive and may be constructed with ease, it will be efficient and generally advantageous. The details disclosed are therefore preferably followed, but within the scope of the invention as claimed, variations may be made.

I claim:—

A stock separator comprising a vertical wall having a rectangular door opening and flat vertical wall portions disposed in a common plane but at opposite sides of said opening, a door for said opening of less width

than the latter, means hinging the door to the vertical wall portion at one side of said opening with its free edge spaced from the vertical wall portion at the other side of said opening, a flat vertical barrier lying slidably against the last named vertical wall portion for adjustment toward or from said free edge of the door, said barrier and said last named wall portion having aligned horizontal slots and bolt holes respectively, clamping bolts passing through said slots and holes for securing said barrier in adjusted position, means for preventing swinging of said door in one direction, and spring means for yieldably holding said door closed.

15 In testimony whereof I have hereunto affixed my signature.

JOSEPH E. LARSON.
